(No Model.)

J. B. ROOT.

MACHINE FOR MAKING SPIRALLY JOINTED METAL PIPE.

No. 280,403.

Patented July 3, 1883.

UNITED STATES PATENT OFFICE.

JOHN B. ROOT, OF PORT CHESTER, NEW YORK.

MACHINE FOR MAKING SPIRALLY-JOINTED METAL PIPE.

SPECIFICATION forming part of Letters Patent No. 280,403, dated July 3, 1883.

Application filed September 10, 1881. (No model.)

To all whom it may concern:

Be it known that I, JOHN B. ROOT, of Port Chester, in the county of Westchester and State of New York, have invented new and useful Improvements in Machines for Making Spirally-Jointed Metal Pipe, of which the following is a specification.

The invention herein described relates to metal pipes or tubing having a spiral seam or joint, and more particularly to such tubing when the seam is formed by welding or soldering, although the rolls, hereinafter described, for the purpose of forcing the edges of the metal strip together would be serviceable for setting down a spiral seam when the edges of the strip are formed to interlock without welding as well as when they simply overlap and are united by the welding process; and it consists of devices to be hereinafter explained.

The invention is fully illustrated in the accompanying drawings, in which Figure 1 is a perspective view of a furnace and seaming-rolls adapted for carrying out the invention, Fig. 2 being a plan, and Fig. 3 being an end elevation, of the same; Fig. 4 is an end elevation of the seaming-rolls, the mandrel or former-block being shown in perspective, Fig. 5 being a similar view of the mandrel and inner roll detached, and Fig. 6 being a plan of such inner roll and former-block. Fig. 7 shows in section the preferred mode of mounting the inner seaming-roll, Fig. 8 being an end view of such roll with the cap removed, and showing also the end of the pin upon which the roll turns. Fig. 9 shows a shell or flask, of plumbago or some equivalent fire-proof material, to be used in heating the metal blank, as hereinafter explained, Fig. 10 being a view of the same in section, and showing also the mandrel and seaming-rolls, and Fig. 11 being a view of seaming-rolls, as seen in elevation, showing the groove and ridge.

Referring to the drawings more in detail, A is the furnace; B, the bed-plate of the machine, placed in immediate proximity to the side of the furnace from which the blank strip C emerges after being heated; D, the upper or outer seaming-roll, mounted upon the shaft E, which in turn is driven by the pulley F; G, the lower or inner seaming-roll, mounted loosely upon the stud or pin H, inserted in the face of the mandrel I. The roll G, instead of being

loose upon a pin, may be made fast to a shaft which has its bearing in the mandrel, and to which power, if desired, can be applied to revolve the roll G. K is a circular guide surrounding the mandrel and co-operating with it to bring the strip into tubular form; L, a tube for feeding a supply of oil or other combustible fluid from any suitable reservoir to the edge of the heated strip of metal; M, a trough or rest for supporting the finished pipe as it feeds off from the mandrel; and L' and L² are tubes or pipes for applying a jet or stream of combustible material to the edges of the winding strip as they are being overlapped.

The operation of the machine, in combination with the furnace, will readily be understood upon an inspection of the drawings. The end of the strip of metal to be wrought, after passing through the furnace, where it is brought to a welding-heat, is entered between the upper side of the mandrel or former-block, which is on a level with the mouth of the furnace, and the lip of the circular guide K. This brings one edge of the strip within the grasp of the two seaming-rolls, which then continue to draw the blank through the furnace and cause it to wind up spirally. As the work progresses the other edge of the strip is carried around an entire turn and thus brought up under the first edge, which overlaps it to an extent determined by the particular adjustment of the machine, and then both edges continue to pass between the seaming-rolls, being thereby subjected to a powerful pressure sufficient to force them into welding contact. The finished pipe feeds off in the direction of the axis of the mandrel, being received upon the rest M.

It will be seen that the edge of the strip which comes under the other in the winding has the longer path to travel after leaving the furnace and before the union is effected. If the metal be such that such edge is liable to cool down too much for welding, the requisite temperature is preserved by the use of a pipe, L, conveying a hydrocarbon oil or other inflammable fluid to a point near to such edge and intermediate between the furnace and the point of welding. The heat produced by the flame at the extremity of such pipe impinging upon the edge of the strip will suffice to keep it up to a welding-temperature.

With many fluids the proximity of the heated metal to the discharge-orifice of the pipe will be sufficient to inflame them as they issue therefrom. A similar appliance is used, when found necessary, in connection with the other side of the strip. The better to maintain the heat in the underlapping edge of the strip, the former-block is cut away or reduced in size, so that such edge of the strip will not come in contact with metal in its passage over and around the block. This construction is shown in Fig. 6, in which the former-block is shown as cutaway at N, and the strip is represented by dotted lines.

15 For manipulating the heated strip for the purpose of drawing the forward end from the furnace and entering it between the rolls, a clutch or pair of tongs, O, is used. These are introduced through the mouth in the front of the furnace and engaged with one side of the strip, as shown in Fig. 2. As soon as the forward end of the strip is grasped by the rolls the entire strip will be drawn forward by the rolls as they continue to revolve. To aid the seaming-rolls in moving the strip through the machine a special pair of rolls is used, arranged in advance of the seaming-rolls, and preferably to bear upon the middle of the upper and lower sides of the strip. Such rolls are shown 30 at P in Figs. 2, 4, and 10.

To accommodate the seaming-rolls to any inequalities in the metal (and these will occur, particularly where the ends of short strips have been united to make up a long strip) the 35 upper roll is mounted in yielding bearings. The outer bearing, Q, of the shaft of this roll is in the form of a sleeve, and is held in the standard R by two horizontal pivots, rr, which mode of mounting permits the bearing, and 40 consequently the shaft, to oscillate within the necessary limits in a vertical plane, rising and falling on these pivots as a center of motion. The inner bearing, S, of this shaft is pivoted in a yoke, T, from which a spindle projects upward in suitable bearings, and is acted upon by a powerful spring, U, which constantly tends to force it downward. This mode of 45 mounting the roller-shaft secures sufficient flexibility to compensate for any inequalities 50 in the work passing between the rolls, and at the same time provides for the requisite pressure of the rolls upon the metal.

The mode of constructing the inner roll, G, and the stud H, on which it is mounted, is 55 specially illustrated in Figs. 7 and 8. The central opening in the roll is conical, and somewhat larger than the end of the stud or pin which projects beyond the face of the mandrel. The upper face of this projecting end 60 of the stud is tapered inwardly, to correspond with the taper of the conical hole of the roll G. The under face of the stud may be left straight. The effect of this construction will be to give the roll freedom of play, notwithstanding the intense heat to which it is subjected, and also to cause it always to hug down 65 against the adjacent face of the mandrel, which,

for such purpose, is formed in a plane perpendicular to the stud. It will also be seen, on examining Figs. 1 and 6, that the stud H, which carries the inner seaming-roll, lies at right angles to the path along which the blank travels, at the point where the rolls act upon it.

By providing the roll G with a cap, V, and also making suitable channels in the mandrel 70 or in the pin H, a flow of water or oil, either alone or mixed with plumbago, can be secured into and out of the central space in the roll, and thus the roll be prevented from overheating.

80 The machine is readily adjusted to the manufacture of different sizes of tubing, as also to tubing made from strips of different widths. To this end the mandrel or former-block, as also the circular guide, is made detachable, 85 which permits others of different size and shape to be substituted; and the rest M is made correspondingly adjustable in a vertical direction, by means of the Y-shaped standards which support it, so as to accommodate it to the different sizes of pipe produced. The rest M and the guide-standard Z are mounted upon a plate, X, which is made capable of swinging around a pivot, t, placed immediately below the seaming-rolls, and which can be secured 90 in any desired position by means of a set-screw working in the circular slot x. By adjusting the position of this plate X the extent of lap can be regulated as may be found desirable, the size of the pipe or the width of 100 the strip remaining the same.

Instead of passing the flat strip directly through the fire of the furnace, as indicated in Figs. 1 and 2, it may, under some circumstances and for some purposes, be found useful to wind it up in a coil before heating, and to secure such coil in a shell or flask of plumbago or other suitable refractory material. This flask is then placed in a furnace, and when the coil of metal has become sufficiently heated the flask and its contents are removed from the furnace and placed near the mandrel and seaming-rolls, when the strip can be drawn from the flask and formed up into spiral tubing in the same way as above described. Such 110 a flask as is here described is shown in Fig. 9, Fig. 10 being a sectional view of it, showing also the mandrel and rolls. Such shell or flask, when used, constitutes, in effect, a secondary furnace.

115 It should be remarked that in coiling the blank to be heated in the flask its surfaces, except at the edges, may be coated with lime-wash or other equivalent material, to prevent them from adhering when brought to a welding-heat.

120 Instead of heating the strip to a welding-heat in a furnace or in a shell or flask, as above described, before it is wound spirally into tubular form, the strip is heated in any desired 125 manner to less than a welding-heat; or, if not too thick, it is wound cold, and by the application of combustible fluids directed in a state of ignition upon the edges thereof, just before

or as they overlap to form the seam or joint, they may be brought up to the desired temperature to be welded in the same way and by the use of the same devices above described.

5. This method is especially applicable to the use of strips of tinned plate—that is, iron covered with tin—in which the tin will be easily melted, and the seam can be formed by soldering the edges together. The construction for applying the combustible fluids for this purpose is shown in Fig. 2, in which L' and L^2 represent two tubes or pipes, one of which may be used to supply oil or any other combustible fluid, and the other to carry a jet of air, which, by 10 contact with the stream of oil near the meeting edges of the strip, will produce the required heat, which can be regulated by the force of the air-jet. This air-jet of course can be made to carry any required flux, or soldering or brazing material.

Instead of using oil or other similar fluid with the air-jet, two gases—like oxygen and hydrogen—may be employed, each conveyed to the desired point near the meeting edges of 15 the strip in separate tubes or pipes and then brought together. In case the strip is not heated hot enough to fire the combustible fluids or gases, a small continuous flame is kept burning near and under the point of junction of the tubes.

30. What is claimed as new is—

1. In a machine for making spirally-jointed

metal pipe, the combination of a mandrel or former-block and an internally-acting seaming-roll arranged upon the end of such mandrel and loosely mounted upon a conical axis at right angles to the line of movement of the metal strip at the point where the roll acts upon the metal.

2. The combination, in a pipe-forming machine, of a seaming-roll constructed with a conical central opening, and a pin or stud for supporting the same, tapered upon one of its sides to fit the wall of the conical opening of the roll, substantially as and for the purpose 45 described.

3. In a spiral-pipe forming and welding machine, a mandrel or former-block cut away or reduced throughout a portion of its extent, substantially as shown and described, so as to 50 permit one edge of the heated blank, as it comes from the furnace, to pass over the mandrel without contact with it, for the purpose set forth.

4. The swinging plate X , provided with the cylindrical guide K for adjusting the mandrel to positions suited to different sizes of pipe and different widths of strips, and for regulating the lap.
